BUCKLE FOR STRAPS AND THE LIKE

William A. Bedford, Jr., North Scituate, Mass., assignor to United-Carr Fastener Corporation, Cambridge, Mass., a corporation of Massachusetts

Application September 23, 1947, Serial No. 775,645

2 Claims. (Cl. 24—198)

1

The present invention relates to buckles and like fasteners and more particularly to buckles of the type having spaced strap-receiving slots as are commonly employed in connection with belts, straps and the like, and the invention aims generally to improve existing buckles of that type.

A primary object of the invention is the provision of a buckle of the type above referred to capable of readily receiving a strap or belt of material normally too thick to be threaded through the spaced slots of the buckle.

Other aims and objects of the invention will be apparent to persons skilled in the art from a consideration of the accompanying drawings and annexed specification, illustrating and describing a preferred construction embodying the invention.

In the drawings:

Fig. 1 is an enlarged perspective view of a preferred form of buckle embodying the invention shown as applied to a strap illustrated in phantom lines;

Fig. 2 is an enlarged transverse section of a buckle in its open position to receive a strap;

Fig. 3 is a sectional view similar to Fig. 2, showing the buckle in closed position; and

Fig. 4 is a perspective view of a modified form of buckle embodying the invention.

Referring to the drawings, the invention relates primarily, though not exclusively, to that type of buckle having a frame and a center piece spaced from the frame ends, providing slots through which a belt, strap or the like is woven or threaded. Such buckles may have associated therewith a suitable fastener part or device for connection with a cooperating fastener part, usually secured or attached to an opposite end of the strap, and such fastener part or device may be associated with a frame end or center piece, as desired, and as will be understood by those skilled in the art. For purposes of illustration, I have shown the invention as embodied in a buckle of the elongated frame and center piece type having a snap fastener part associated with the center piece.

One embodiment of the invention is shown in Figs. 1, 2 and 3 in which the buckle comprises an elongated frame 10 of suitable sheet material, for example sheet metal, having side portions 11 and end portions 12, and providing a central opening 10a. The center piece 13 may be integrally connected with the frame along one side edge, as at 14, thereof, and has end edges 15 spaced from the end portions 12 of the frame to provide spaced slots 16. The opposite side edge 17 of the

2

center piece 13 is separate from the adjacent frame side bar 11, and normally the center piece is disposed in a plane oblique to the plane of the frame 10, as shown in Figs. 1 and 2, to provide an open throat between the edge 17 of the center piece and the adjacent edge of the frame side bar 11 through which the strap or belt may be moved laterally to be positioned over the frame end bars 12 and under the center piece 13 as viewed in Figs. 1 and 2.

The buckle in its open condition, as viewed in Figs. 1 and 2, may be readily assembled with a strap, belt or the like merely by slipping the strap laterally edgewise beneath the center piece 13 and over the frame end bars 12 and thereafter depressing the center piece into the plane of the frame 10.

Suitable means are provided on one edge of the side bar 11 adjacent the free edge 17 of the center piece, for engaging the edge 17 and holding the center piece 13 in the plane of the frame 10. According to the form of invention shown in Figs. 1, 2 and 3, the inner edge of the side bar 11 may be formed with an angularly extending lip 18 adapted to be deformed or clenched into overlying relation with the free edge portion 17 of the center piece 13, as shown in Fig. 3, and thus secure the center piece 13 in the plane of the frame 10. It will be noted that the section of the frame 11 adjacent the lip 18 may be transversely curved as at 11a so that the inner free edge of the lip 18 is disposed above the plane of the buckle frame 11 a distance greater than the spacing between the lip 18 and the free edge 17 of the center piece.

The center piece 13 preferably has associated therewith a fastener element adapted for fastener cooperation with a cooperating fastener preferably secured to a spaced end portion of the strap, belt or the like. In the illustrated embodiments the fastener member advantageously is a snap fastener stud member though it will be understood that other forms of fastener may be used.

As illustrated in Figs. 1, 2 and 3, the fastener member comprises a stud 20 having a base 21 and secured to one face of the center piece 13, which may be slotted as at 22, by an attaching member 23 preferably in the form of an eyelet upset within the stud. This method of securing a stud member to an apertured supporting part is old per se and forms no part of the present invention, other than as one suitable means for embodying a fastener part with the buckle. Alternately, the stud member 20a may be drawn

from the body of the center piece 13 as an integral part thereof, as shown in Fig. 4.

The center piece 13 of the buckle preferably has associated therewith a strap-gripping means for gripping the material of a strap or belt disposed between the center piece and the frame member. According to the form of invention shown in Figs. 1, 2 and 3, the strap-gripping means may comprise toothed or serrated edges 25 on the fastener attaching member 23, which is shiftable in the slot 22, and thus may be moved into biting or gripping engagement with the strap. Alternatively, the strap-gripping means may be in the form of prongs, teeth or serrations 25a on the edge portions of the center piece 13 opposite the frame end bars 12 as is shown in Fig. 4.

From the above it will be apparent that the invention provides a buckle of simple construction, which may readily be assembled with straps, belts and the like of such bulky and thick material as not to be passable through the slots between the center piece 13 and the frame end portions 12.

While I have illustrated and described one preferred embodiment of the invention, I do not intend to be restricted thereto as the scope of the invention is best defined in the appended claims.

I claim:

1. A buckle comprising a frame having opposed side portions and opposed spaced end bars providing a strap-receiving opening therebetween, a center piece integral with said frame and extending laterally from one of said side portions across said opening, the free side edge of said center piece being disposed in a plane immediately adjacent a portion of the inner edge of an adjacent side portion and said center piece being of a length substantially less than the distance between the inner edges of said end bars to form strap-receiving slots therebetween, a section of the frame side portion adjacent the free

edge of said center piece being transversely curved to provide an angularly extending retaining lug on the inner edge of said side portion of greater width than the spacing between the free edge portion of said center piece and adjacent portion of said side portion, said center piece normally extending at an angle to its connected frame side portion to be disposed in inclined relation to the plane of the frame and with the free side edge thereof disposed above the free upper edge of said retaining lug to provide an open throat therebetween for the ready insertion of a strap between said center piece and above the frame end bars, said center piece being bendable into the plane of the side bars of said buckle and said retaining lug being bendable into overlapping relation with the free side edge portion of said center piece.

2. A buckle as defined in claim 1 wherein the end edges of the center piece opposite the frame end bars are serrated.
